OIL BURNER CONTROL

Philip S. Arnold, Flint, Mich.

Application May 13, 1936, Serial No. 79,554

6 Claims. (Cl. 236—87)

This invention relates to oil burner controls and the object of the invention is to provide a pneumatic control for use in connection with a compressed air operated oil burner which is started by closing all escape passages and allowing pressure to be built up in the system by a constant output air pump and stopped by opening an escape passage and allowing the pressure to drop.

Another object of the invention is to provide a thermostat arranged to operate a mechanism whereby the air passages may be controlled so that when the air passages are opened the pressure is allowed to drop to shut off the burner and when the air passages are closed the pressure is allowed to build up to start the burner.

A further object of the invention is to provide a device which is entirely automatic in operation as governed by the room temperature and requires no manual re-setting.

Another object of the invention is to provide a lever which when turned to one position will open the escape valve and when turned to the other position will close the escape valve, the movement of the lever being controlled by the thermostat in combination with the air pressure of the system.

These objects and the several novel features of the invention are hereinafter more fully described and claimed and the preferred form of construction by which these objects are attained is shown in the accompanying drawing in which—

Fig. 1 shows the device in operating position with the pressure built up.

Fig. 2 shows the device in non-operating position with the escape valve open.

Fig. 3 is an enlarged view taken on line 3—3 of Fig. 2.

The device comprises a casing 1 having vent apertures 2 shown in Figs. 1 and 2. A circular member 3 is secured to the bottom of the casing by the bolt 4 and this member 3 is provided with an upwardly extending lug 5 at one side to which the coiled thermostatic element 6 is secured. At the upper end this element 6 is secured to a member 7 which is connected to a pinion 8 rotatably mounted in the bracket 9. This pinion 8 meshes with the teeth in a rack 10 and the rack 10 is pivotally connected at the end opposite the gear 8 to a bracket 11. This bracket 11 is connected to the trigger member 12 which is pivoted at 13 to a stationary bracket 14. A flat spring metal trigger is secured at the center to the member 12 and is provided with downwardly extending ends 15 and 16 which press lightly against the inturned ends 17 of the lugs 18 as shown in Fig. 3.

A cylinder 19 is provided at one side of the casing 1 and a piston 20 is slidably mounted in the cylinder and is provided with an upwardly extending portion 21. A coiled spring 22 is positioned about the portion 21 and at one end engages against the top of the cylinder and at the opposite end engages against the piston 20.

This cylinder 19 at the bottom is provided with an air inlet opening 23 through which air may enter the cylinder from the air conduit 24. The conduit 23 is provided with a vent aperture 25 which may be closed by the valve 26 and when the valve 26 is opened the air may escape through the escape passage 27 into the interior of the casing 1 which is vented to atmosphere by the apertures 2.

A rod 28 is connected to the piston in the cylinder 19 and extends through the top of the cylinder. This rod 28 extends through a guide bracket 29 and is provided with collars 30 and 31 secured to the upper end thereof. A lever 32 is pivotally mounted at 33 on the bracket 34 and the end of this lever is slotted or provided with an elongated aperture through which the rod 28 extends. The lever 32 beneath the pivot 33 is provided with an inturned foot 35 and this foot is arranged to engage the pawls 36 or 37 when the lever 32 is turned to the two positions shown in Figs. 1 and 2. A spring 38 is connected to the end of lever 32 and to a bracket 39 and this spring tends to pull this lever 32 to a neutral position. The pawls 36 and 37 are each provided with a notch in the end thereof adapted to engage over the upturned lugs at the opposite ends of the member 12. The rod 28 is provided with a collar 40 thereon having an extending arm provided with a pin 41 riding in the slot 42 of a pivoted arm 43 which is pivotally connected to the bracket 44. Intermediate the ends of the arm 43 is a link 45 which is pivotally connected thereto and at the lower end is pivotally connected to a bracket 46 having a spring 51 therein. The valve release lever 47 is pivotally mounted on a bracket 48 and is pivotally connected to the link 49 which in turn is connected to the valve 26.

In the position shown in Fig. 1 the valve 26 closes the escape aperture 25 so that the air passing into the cylinder has raised the piston until the portion 21 has engaged the top of the cylinder. In Fig. 1 the parts are in position assumed during operation of the burner. As the temperature of the room rises the thermostatic element 6 turns the gear 8 in a clockwise direction, viewed from the top, thus moving the rack 10 to the right of Fig. 1 and turning the member 12 on the pivot 13 to raise the right end of said

member. This raises the flat spring member 16 above the upper end of the lever 47 and the spring 51 through the bracket 46 turns this lever to the left of Fig. 1 to open the valve 26 as shown in Fig. 2. As the end of the member 16 is raised above the end of the lever 47, this lever 47 may move between the ends 17 of the lugs 18 shown in Fig. 3 and to the left of Fig. 1 until the end of the lever engages beneath the flat spring end 15 which will be raised by the end of the lever until the lever passes out from under the flat spring end 15, at which time, it will engage against said flat spring end 15 as shown in Fig. 2. The opening of the valve 26 allows the air pressure to escape through the apertures 25 and 27 and as the air pressure is reduced in the cylinder 19 the spring 22 forces the piston downwardly. This downward movement of the piston lowers the collar 40 and arm 43 and the link 45 turns the bracket 46 to the position shown in Fig. 2 thus placing a tension on the lever 47 and tending to move it to the right of Fig. 2.

However, this lever cannot move to the right due to its engagement against the end of the spring trigger 15. Also during downward movement of the rod 28 the collar 31 engages the end of the lever 32 and turns it on the pivot 33 until the shoe 35 lifts the pawl 36 to the position shown in Fig. 2. The control mechanism is then in position for subsequent operation with the burner shut off.

As the room cools down, the gear 8 is rotated in a counter-clockwise direction by the thermostat thus moving the rack 10 to the left of Fig. 2 which 35 raises the left end of the member 12 until the member 15 is lifted above the upper end of the lever 47. At this time the spring 51 acting through the bracket 46 turns the lever 47 to the right of Fig. 2 so that the upper end thereof passes under 40 the flat spring 16 to the position shown in Fig. 1. This movement of the lever 47 closes the valve 26 so that the air pressure passes through the passageway 23 into the cylinder 19 and raises the piston 20 to the position shown in Fig. 1 against 45 the tension of the spring 22. During this movement, the collar 40 is raised to raise the lever 43 and link 45 to place a tension on the lever 47 to throw it to the left of Fig. 1. Also, the collar 30 in moving upwardly moves the shoe 35 so that 50 the notch in the pawl 36 may engage the left end of the member 12 and as the piston reaches the top of its stroke the shoe 35 lifts the pawl 37 off from the right hand end of the member 12 so that the control is again ready for another 55 operation. The pawls 36 and 37 prevent the trigger member 12 from releasing the lever 47 until the spring 51 has been given tension enough so that it will force the lever 47 through its entire stroke when released.

60 The temperature at which the thermostat will operate may be varied by loosening the nut 52 on the bolt 4 and turning the disc 3 to vary the position of the lug 5 radially about the bolt 4. By this adjustment the thermostat may be set to 65 operate the control at the desired temperature. Though not here shown, the conduit 24 is supplied with air under pressure by a constant output air pump which maintains a continuous air supply.

From the foregoing description it becomes evident that the device is very simple and efficient in operation, will automatically control an oil burner by opening or closing the air escape, may be adjusted for various temperatures and provides a device which accomplishes the objects 75 described.

Having thus fully described my invention, its utility and mode of operation, what I claim and desire to secure by Letters Patent of the United States is—

1. An oil burner control comprising a perforated 5 casing, a cylinder mounted in the casing, an air conduit opening into the bottom of the cylinder, a vent valve for the air conduit, a lever pivotally mounted in the casing and turnable to one position to close the vent valve and turnable to another position to open the vent valve, a trigger pivotally mounted adjacent the free end of the lever and turnable on its pivot to move one end or the other of the trigger into the path of travel of the lever, a thermostat connected to turn the 10 trigger on its pivot, a piston movable upwardly in the cylinder by air pressure, a spring tending to move the piston downwardly in the cylinder, means connected to the piston for applying pressure to turn the lever in one direction as the piston moves upwardly, said means being arranged for applying pressure to turn the lever in the other direction as the piston is moved downwardly in the cylinder, a pair of pawls pivotally mounted 15 in the casing and arranged to engage the ends of the trigger to prevent movement of the trigger on its pivot and means connected to the piston for raising one pawl as the piston reaches the top of its stroke and for raising the other pawl as the piston reaches the bottom of its stroke. 20

2. An oil burner control comprising a perforated casing, a cylinder mounted in the casing, an air conduit opening into the bottom of the cylinder, a vent valve for the air conduit, a lever pivotally mounted in the casing and turnable to one position to close the vent valve and turnable to another position to open the vent valve, a trigger pivotally mounted adjacent the free end of the lever and turnable on its pivot to move one end or the other of the trigger into the path of travel of the lever, a thermostat connected to turn the trigger on its pivot, a piston movable upwardly in the cylinder by air pressure, a spring tending to move the piston downwardly in the cylinder, means connected to the piston for applying pressure to turn the lever in one direction as the piston moves upwardly, said means being arranged for applying pressure to turn the lever in the other direction as the piston is moved downwardly in the cylinder, a pair of pawls pivotally mounted 25 in the casing and arranged to engage the ends of the trigger to prevent movement of the trigger on its pivot and means connected to the piston for raising one pawl as the piston reaches the top of its stroke and for raising the other pawl as the piston reaches the bottom of its stroke. 30

3. An oil burner control comprising a perforated casing, a cylinder mounted in the casing, an air conduit opening into the bottom of the cylinder, a vent valve for the air conduit, a lever pivotally mounted in the casing and turnable to one position to close the vent valve and turnable to another position to open the vent valve, a trigger pivotally mounted adjacent the free end of the lever and turnable on its pivot to move one end or the other of the trigger into the path of travel of the lever, a thermostat connected to turn the trigger on its pivot, a piston movable upwardly in the cylinder by air pressure, a spring tending to move the piston downwardly in the cylinder, means connected to the piston for applying pressure to turn the lever in one direction as the piston moves upwardly, said means being arranged for applying pressure to turn the lever in the other direction as the piston is moved downwardly in the cylinder. 35

4. An oil burner control comprising a perforated casing, a cylinder mounted in the casing, an air conduit opening into the bottom of the cylinder, a vent valve for the air conduit, a lever pivotally mounted in the casing and turnable to one position to close the vent valve and turnable to another position to open the vent valve, a trigger pivotally mounted adjacent the free end of the trigger, spring means for turning the lever on its pivot, a piston slidably mounted in the cylinder and movable upwardly by air pressure within the cylinder, a spring tending to move the piston downwardly and means operated by the piston for applying pressure to said lever on one side or the other of its pivot. 40

5. An oil burner control comprising a perforated casing, a cylinder mounted in the casing, an air conduit opening into the bottom of the cylinder, a vent valve for the air conduit, a lever pivotally mounted in the casing and turnable to one position to close the vent valve and turnable to another position to open the vent valve, a trigger pivotally mounted adjacent the free end of the trigger, 45

the lever and turnable on its pivot to move one end or the other of the trigger into the path of travel of the lever, a thermostat connected to turn the trigger on its pivot, a piston movable upwardly in the cylinder by air pressure, a spring tending to move the piston downwardly in the cylinder and means connected to the piston for applying pressure to the lever at one side or the other of its pivot.

5 5. An oil burner control comprising a perforated casing, a cylinder in the casing, an air conduit opening into the bottom of the cylinder, a vent valve for the air conduit, a lever pivotally mounted in the casing and turnable to one position to close the vent valve and to another position to open the vent valve, spring means arranged for turning the lever on its pivot, a trigger pivotally mounted adjacent one end of the lever and turnable on its pivot to move one end or the other of the trigger into path of travel of the lever, a thermostat connected to turn the trigger on its pivot, spring means applicable to the lever on one side or the other of its pivot to turn the same in one direction or the other and pneumatically operated means for controlling the application of the spring means to the lever.

10 10 15 15 20

in either direction, a piston in the cylinder and means connected to the piston to control the application of the spring means to move the lever in one direction or the other.

6. An oil burner control comprising a perforated casing, an air conduit, a vent valve for the air conduit, a lever pivotally mounted in the casing and turnable to one position to close the vent valve and to another position to open the vent valve, spring means arranged for turning the lever on its pivot, a trigger pivotally mounted adjacent one end of the lever and turnable on its pivot to move one end or the other of the trigger into path of travel of the lever, a thermostat connected to turn the trigger on its pivot, spring means applicable to the lever on one side or the other of its pivot to turn the same in one direction or the other and pneumatically operated means for controlling the application of the spring means to the lever.
